UNITED STATES PATENT OFFICE.

CHARLES A. LIEB, OF NEW YORK, N. Y.

BOOK AND PAMPHLET TRIMMING MACHINE.

SPECIFICATION forming part of Letters Patent No. 334,672, dated January 19, 1886.

Application filed April 22, 1885. Serial No. 163,002. (No model.)

To all whom it may concern:

Be it known that I, CHARLES A. LIEB, of the city, county, and State of New York, have invented, made, and applied to use improvements in the construction of blocks to be used in connection with machines for trimming books and pamphlets; and I do hereby declare that the following is a full, clear, and correct description of my invention, reference being had 5 to the accompanying drawings, making part of this specification, and to the letters of reference marked thereon, in which—

Figure 1 is a side elevation of my invention. Fig. 2 is a top view of the same. Fig. 3 is a 15 top view of the block extended. Fig. 4 is a view of the central section, a^3 . Fig. 5 is a view of one of the sections. Fig. 6 is a side view of Fig. 5. Fig. 7 is a view of one of the sections a^4 a^5 . Fig. 8 is a view of the under 20 side of the upper surface.

In the drawings like parts of the invention are designated by the same letters of reference.

The nature of my invention consists in the 25 construction, as more fully hereinafter set forth, of an improved block to be used in connection with machines for trimming books and pamphlets, the object of the invention being the production of a block for this purpose capable of adjustment lengthwise and crosswise, 30 so as to accommodate it to books or pamphlets of different sizes. The block is attached to the portion of the machine directly above the table upon which the pile of books or 35 pamphlets is placed, and forms, as it were, an upper clamping-surface, between which and the table the pile of books or pamphlets is clamped, and at the same time serves as a guide to the knife of the machine by which 40 the trimming is done. It is made adjustable both crosswise and lengthwise, so that when attached in position upon the machine it can be adjusted to different sizes of books or pamphlets to be trimmed, thus saving time 45 and expediting the work required of the machine.

To enable those skilled in the arts to make and use my invention, I will describe the same.

The improved block may be said to be composed of an under and an upper surface. The under surface is composed of the sections a , a^2 ,

a^3 , a^4 , and a^5 . The sections a and a^2 are provided at one end and on the side with the projecting ledge or raised surface b , and at the opposite end the metal is beveled, as at c , so 55 as to present, as it were, a knife-edge; or this portion of the lower surface may be made separately and riveted to the sections a and a^2 . The sections a and a^2 are grooved, as at d , to allow the cross-bar e of the central section, a^3 , 60 to be received and move freely in the same. The sections a and a^2 are also provided with the tongues f , moving freely in the grooves g of the sections a^4 and a^5 .

a^3 shows the central section of the lower 65 surface, provided with the projecting ledge or raised surface h at one end, and also with the cross-bar e , received and moving freely in the grooved ways d of the sections a and a^2 . The remaining sections of the under surface, a^4 70 and a^5 , are provided on the sides with the projecting ledge or raised surface i , and when placed in position project beyond the beveled ends of the sections a and a^2 , the tongues f of which are received and move freely in the 75 grooves g .

The sections a , a^2 , a^4 , and a^5 are provided with screw-holes k , for the reception of the bolts l , employed to hold the sections together, and the section a^3 is necessarily made shorter 80 than the sections a and a^2 .

The upper surface of the block consists simply of the plate of metal m , formed in one piece, provided with the oblong openings n and the nearly-square openings o . It is also 85 grooved, as at p , to receive guides 2, placed upon the section a^3 , and upon its upper side is provided with a standard, q , by which it may be attached to the machine with which it is to be used, the standard q passing through 90 an opening in the machine, and being fastened by a nut, s , engaging with the threaded end of the standard q . The upper and under surfaces thus constructed are placed in proper positions by placing the upper surface upon 95 and within the lower surface, and are secured together by bolts l , passed through the oblong openings n and nearly-square openings o , and entering into the screw-holes k .

The operation may be thus described: The 100 block composed of the two surfaces secured together, as described, is attached to the up-

per portion of the book or pamphlet trimming machine, directly above the table upon which the books or pamphlets to be trimmed are placed, and bears upon the upper surface 5 of the same. It is adjustable laterally to the extent of the openings in the upper surface by loosening the bolts passed through the same into the sections of the lower surface and moving sections a , a^2 , a^4 , and a^5 sidewise 10 and lengthwise by moving the sections a^4 and a^5 away from the sections a a^2 .

It will be seen that the block can be readily altered to accommodate itself to books of different widths and lengths, and that this adjustment can be made rapidly and without the necessity of removing the block from the ma-

chine, by which the work of the machine is necessarily quickened.

Having now set forth my invention, what I claim as new is—

In a block for book and pamphlet trimming machines, the combination of the following elements: the sections a , a^2 , a^3 , a^4 , and a^5 , an upper plate, m , provided with the openings n and o and standard q , and the bolts l , all constructed and operating substantially as and for the purposes set forth.

CHARLES A. LIEB.

In presence of—

WILLIAM V. H. HICKS,
A. SIDNEY DOANE.
